(57) **CLAIM**

The ornamental design for a side-mounted fuel tank, as shown and described.

DESCRIPTION

FIG. 1 is a top perspective view of a side-mounted fuel tank, showing our new design;

FIG. 2 is a top plan view thereof;

FIG. 3 is a front view thereof;

FIG. 4 is a left side view thereof; and,

FIG. 5 is a right side view thereof.

The broken lines adjacent the shaded surfaces in the figures represent boundaries, while the other broken lines represent unclaimed environmental structure. None of the broken lines form part of the claimed design.
